UNITED STATES PATENT OFFICE.

HAROLD D. CHURCH, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,339,497.

Specification of Letters Patent. Patented May 11, 1920.

Application filed June 26, 1916. Serial No. 105,880.

To all whom it may concern:

Be it known that I, HAROLD D. CHURCH, a citizen of the United States, and resident of Detroit, Wayne county, State of Michigan, have invented certain new and useful improvements in Hydrocarbon-Motors, of which the following is a specification.

This invention relates to hydrocarbon motors, and particularly to governing mechanism therefor.

One of the objects of the invention is to provide a simple and compact arrangement of governor and throttle connections on a hydrocarbon motor.

Another object of the invention is to provide a governor unit that may be readily attached to and detached from a motor.

Another object of the invention is to arrange the governor and throttle relatively close together so that the connections between them may be readily housed.

Another object of the invention is to provide a novel housing for the connections between the governor and the throttle valve.

Another object of the invention is to provide a governor unit of novel construction.

Other objects of the invention will appear from the following description taken in connection with the drawings which form a part of this specification; and in which—

Figure 1 is a transverse vertical section through a hydrocarbon motor embodying this invention.

Fig. 2 is a horizontal section substantially on the line 2—2 of Fig. 1.

Fig. 3 is a section substantially on the line 3—3 of Fig. 1.

Fig. 4 is a transverse horizontal section through the governor and casing; and

Fig. 5 is a vertical section substantially on the line 5—5 of Fig. 3.

Referring to the drawings, 10 represents the crank case of a hydrocarbon motor in which is mounted a cam shaft 11 driven from the motor crank shaft as by gears 12 and 13 indicated diagrammatically in dotted lines. The cam shaft 11 is provided with a spiral gear 14 which forms the driving gear for a governor hereinafter described.

The motor cylinders 15 are shown as formed in a block and suitably mounted on the crank case. Two of the cylinders are shown in section in Fig. 2, and in the space between them a governor unit 16 is mounted.

This governor unit is self-contained and

it comprises a lower casing 17, and a detachable upper casing 18 and a governor 19 arranged therein. The governor 19 comprises a main shaft 20 mounted in bearings at opposite ends of the casing, and a block 21 secured to said shaft and having arms 22 upon which bell cranks 23 are pivotally mounted as at 24. The free ends of the bell cranks 23 are formed with weights 25 such as shown in Figs. 1 and 4, and the other arms of the bell cranks engage in a sleeve 26, which is adapted to slide on the shaft 20. A spring 27 surrounding the shaft presses the sleeve 26 downwardly and adjusting nuts 28 at the upper end of the shaft determine the tension on the spring. There is an opening 29 in the side of the upper casing member 18 which gives access to the adjusting nuts 28 and this opening is closed by a detachable cover 30. Suitable stops 31 and lugs 32 on the arms 22 and bell cranks 23 respectively, determine the limit of operation of the governor.

The governor shaft 20 extends through the lower end of the casing and a spiral gear 33 is connected to the projecting end. The casing is so formed that its lower end may be inserted through an opening 34 in the upper face of the crank case between two of the cylinders, and thus be positioned properly for the gear 33 to mesh with the gear 14 on the cam shaft 11. A flange 35 on the governor casing provides means for securing the governor unit to the crank case.

A cylinder head 36 is mounted on top of the cylinders and is formed with an inlet passage 37 for the various cylinders. A carbureter 38 of suitable form is connected to the cylinder head to supply the passage 37 by means of an intake pipe 39, which is attached to the cylinder head directly above the governor unit. At the upper end of the intake pipe 39 is a throttle valve 40 pivoted at 41, particularly as shown in Figs. 1 and 3. At one side of the intake pipe 39 adjacent the throttle valve is a chamber 42, the walls of which are partly formed integral with the intake pipe and partly by a cover 43. This chamber houses an arm 44 which is secured to the pivot pin 41 of the throttle valve 40 for operating the latter. A vertical section through the chamber 42 is shown in Fig. 5, and it will be seen that an adjustable stop 45 is positioned in the lower wall thereof to limit the movement of the end of

the arm 44. This adjustable stop determines the minimum degree of opening of the throttle valve.

Between the ends of the arm 44 an operating rod 46 is pivotally connected as at 47, and this rod extends downwardly through an opening in the chamber 42 and through a tube 48, which connects the interior of the chamber 42 with the interior of a hollow arm 49, which is shown as projecting laterally from the governor casing. Pivotally mounted at 50 in the governor casing and extending into the hollow arm 49, is a lever 51 which is pivotally connected to the vertical rod 46 at 52. The opposite end of the lever 51 is pivotally connected at 53, as particularly shown in Figs. 1 and 2, to a yoke 54, which operates in an annular groove 55 in the sleeve 26 of the governor. By the above arrangement it will be seen that all of the connections between the governor and the throttle valve are incased, and by sealing the various covers to the casing the governor and connections may be insured against tampering with.

It is believed that the operation of the governor and its connections is sufficiently clear from the above description without further explanation.

It will be understood that other forms may be made without departing from the spirit or scope of this invention.

Having thus described my invention, what I claim and desire to secure by Letters Patent is:—

1. A governor unit comprising a lower casing member and an upper casing member, a governor shaft journaled in the casing, a flyball governor mounted on said shaft, an adjusting device for the governor at the upper end of said shaft, said upper casing member having an opening to give access to said device, and a cover for said opening.

2. In a hydrocarbon motor, in combination, a motor intake pipe, a throttle valve therein, an arm for operating said valve, an adjustable stop on the intake pipe against which the end of said arm is adapted to abut to determine the minimum degree of opening of the valve, and an operating rod connected to the arm between its ends.

3. In a hydrocarbon motor, in combination, a crank case, a governor casing mounted thereon and having a hollow arm extending therefrom, a governor in the casing, an intake pipe connected to the motor cylinder and having a chamber in one side, a tube extending from said hollow arm to said chamber, and connections from the governor to the motor throttle extending through said tube.

4. In a hydrocarbon motor, in combination, a crank case, a governor casing mounted thereon and having a laterally extending hollow arm, a governor in the casing, an intake pipe connected to the motor cylinders above the governor and having a chamber in one side, a throttle valve in the intake pipe adjacent said chamber, a tube extending from said hollow arm to said chamber, and connections from the governor to the throttle extending through said tube. 65

5. In a hydrocarbon motor, in combination, a motor crank case, cylinders thereon, a governor unit arranged vertically between two of the cylinders, an intake pipe connected to the cylinders directly above the governor, a tube leading from the casing of the governor unit to said intake pipe, and throttle control connections extending from the governor through said tube to the intake pipe. 75

6. In a hydrocarbon motor, in combination, a motor crank case, cylinders thereon, a governor unit arranged vertically between two of the cylinders, an intake pipe at the top of the motor, a throttle valve therein, a tube leading from the governor unit to said intake pipe, and connections from the governor to the throttle valve through said tube. 85

7. In a hydrocarbon motor, in combination, a motor crank case having an opening therein, a shaft in the crank case having a gear thereon, a governor casing and governor therein, and a gear for driving the governor, said casing being adapted to be partly inserted through said opening to engage the governor gear with the gear on 95 said shaft.

8. In a hydrocarbon motor, in combination, a motor crank case having an opening therein, a shaft in said crank case having a gear thereon, a self contained governor unit including a casing for inclosing the governor mechanism and having a gear adapted to be inserted through the opening in the crank case to engage the gear on said shaft. 105

9. In a hydrocarbon motor, in combination, a crank case having an opening therein, a shaft in the crank case having a gear thereon, a self-contained governor unit having a casing adapted to be inserted through said opening, said casing having a flange 115 adapted to engage and be secured to said crank case, said unit also including a gear insertible with the unit through said opening and adapted to engage the gear on said shaft. 120

In testimony whereof I affix my signature.

HAROLD D. CHURCH.
